Harry H. Still

ATTORNEY

UNITED STATES PATENT OFFICE.

DENIS HENRY O'MEARA, OF DETROIT, MICHIGAN, ASSIGNOR TO AMERICAN OPTICAL COMPANY, OF SOUTHBRIDGE, MASSACHUSETTS, A VOLUNTARY ASSOCIATION OF MASSACHUSETTS.

MAGNIFIER.

Application filed September 25, 1924. Serial No. 739,862.

This invention relates to improvements in magnifiers, and has particular reference to magnifiers which are especially adapted for reading or close inspection work.

5 An important object of the present invention is to provide a magnifier whereby a lens may be positively held at a definite distance from the object being viewed.

Another object is to provide such a device 10 wherein the lens may be adjusted to different positions so as to be capable of use in different ways.

Another object is to provide such a device 15 wherein the lens will be securely held in the various selected positions.

Another object is to provide such a device which will be compact and conveniently portable.

Other objects and advantages should be 20 apparent from the following specification when taken in connection with the accompanying drawings, wherein is shown for the purposes of illustration one embodiment of the invention.

25 In the drawings:

Figure 1 is a front elevation of a preferred form of the invention;

Figure 2 is a side elevation thereof;

Figure 3 is a vertical sectional view on the 30 line 3—3 of Figure 1;

Figure 4 is a side elevation illustrating the lens in an adjusted position;

Figure 5 is a front elevation of the device as shown in Figure 4;

35 Figure 6 is a similar view showing the lens in still another operative position;

Figure 7 is a front elevation showing the lens completely extended from its supporting frame;

40 Figure 8 is a fragmentary sectional view on the line 8—8 of Figure 7; and

Figure 9 is a side elevation of the device illustrating still another possible operative position.

45 Referring particularly to Figures 1, 2 and 3, it will be seen that an open frame member 10 is provided preferably of annular form, said frame being split as at 11, and having reduced meeting ends 12 at its split portion.

A pair of finger grips 13 are provided, as 50 shown, secured to the frame 10 and spaced from each other, preferably an equal distance from the meeting ends 12. While these finger grips 13 may be of any suitable shape, I have illustrated them as being in the 55 form of curved ears extending in a general outward direction, and as best shown in the side elevation, their central portion is widened as at 14 for the purpose of ready manipulation. The frame member 10 and 60 the finger grips 13 may be integrally formed as by an aluminum or bronze casting, or they may be made of separate pieces brazed or soldered together.

A continuous lens rim 15 is adapted to 65 carry a magnifying lens 16 of any suitable optical power, and extending outwardly from one side of the rim 15 are a pair of lugs 17, which are suitably apertured and hingedly mounted upon the reduced meeting ends 70 12 of the split frame. The diameter of the rim 15 is slightly less than the internal diameter of the frame 10, and the two members are eccentrically positioned with relation to one another so that the periphery of 75 the rim 15 comes in frictional contact with the inner surface of the frame 10 at the point 18. By this arrangement it will be obvious that when the lens and its containing rim are folded onto the frame member 80 10 they will be securely held in place by virtue of the frictional contact.

In the use of this magnifier the finger grips 13 may be held while the lens is in the position as shown in Figure 1 so as to be 85 used as a simple magnifier or reading glass. If desired, the lens containing rim 15 may be swung outwardly from the frame 10 to a position at right angles thereto, as clearly shown in Figures 4 and 5. When this is 90 done the bottom edge of the frame 10 may be rested upon a table or other suitable working surface, upon which the object to be magnified is placed, and because of the fact that the width of the frame member 10 is 95 substantially equal to the focal length of the lens 16 good results may be had. It will be seen that in this form the focal distance of

the lens may always be accurately maintained, which will be convenient in certain classes of work, or where the lens has to be used quite frequently.

5 In Figure 6 is illustrated another method of using the device, wherein the lens rim 15 is swung into a position at right angles to the frame 10, similar to that shown in Figure 4, after which the whole structure is 10 rolled slightly upon the periphery of the frame member 10, whereby the lens is positioned at an angle in relation to the supporting table. Some people may desire to use the instrument in this way, and here also 15 as in the preceding form, the focal distance may always be accurately maintained.

Some people might find the finger gripping portions 13 too small for their own individual use and, therefore, require a 20 larger gripping means. If so, they need only to swing the lens rim 15 through an arc 180 degrees, whereby it will be completely extended from the frame 10, as clearly shown in Figure 7. It will be here noted that the 25 form of the grips 13 and the distance between them is so designed that when the lens is in this extended position there will be frictional contact between the lens rim and the ears 13, as at the point of tangency 19. 30 Thus when the lens is so extended it will be firmly held in such operative position and the person using same may grasp the frame 10 in the palm of his hand and the finger grips 13 between his fingers, as will be readily apparent.

In Figure 9 the lens rim is shown in an intermediate position, whereby it may be used as a reading glass, the whole frame member 10 resting upon the surface of the book or 40 other object being viewed and the vision through the lens being oblique.

By forming the meeting ends of the frame 10 to a reduced diameter as at 12, a pair of shoulders 20 are produced and it is to be 45 noted that the normal distance between said shoulders is slightly less than the distance between the outer surfaces of the ears 17. With this construction, it is necessary, in order to assemble the lens rim 15 in the frame 50 10 that the open end of the frame be forced apart so that the reduced ends 12 may be slipped into the ears 17. Thus the frame 10 is constrained from returning to its initial form and as 55 a consequence there is always a frictional contact by the shoulders 20 against the surfaces of the pivot ears 17 whereby the rim 15 may be adjusted to several different positions and such adjusted positions maintained 60 by the frictional contact.

From the foregoing it will be obvious that an improved magnifier has been produced, which will be capable of many uses, and in view of the fact that it is so readily foldable 65 it may easily be carried in a pocket or purse,

etc. The device is neat in appearance and will be strong and durable in service. Obviously, changes may be resorted to in the minor details of construction, and the right is herein reserved to make such changes falling within the scope of the claims without departing from the spirit of the invention. 70

Having thus described my invention, I claim:

1. A device of the character described 75 comprising a surrounding open frame, a lens pivoted within the frame so as to lie within the open frame in the plane thereof and also so as to be swung at right angles to the frame on its pivot, the height of said frame 80 being equal substantially to the focal length of the lens.

2. In a device of the character described 85 comprising a surrounding open frame, a lens pivoted within the frame so as to lie therewithin in the plane of the frame and also so as to be swung on its pivot to desired angle with the frame, extending spaced members on the outside of the frame adapted to frictionally engage between them the periphery of the lens when it is rotated substantially 180 degrees on its pivot from its position within the frame and to hold the lens therebetween in extended position. 90

3. A device of the character described 95 comprising a surrounding open frame, a lens pivoted within the frame so as to lie therewithin in the plane of the frame and also so as to be swung on its pivot to desired angle with the frame, extending spaced 100 members on the outside of the frame adapted to frictionally engage between them the periphery of the lens when it is rotated substantially 180 degrees on its pivot from its position within the frame and to hold the lens therebetween in extended position. 105

4. In a device of the character described, 110 a surrounding open frame, a lens pivoted within the frame so as to lie therewithin in the plane of the frame, means adapted to hold the frame in extended position when it has been rotated substantially 90 degrees 115 on its pivot, the height of the frame being substantially the same as the focal length of the lens, and extending means adapted to frictionally hold between them the periphery of the lens when it has been rotated substantially 180 degrees on its axis. 120

5. In a device of the character described, 125 an open surrounding frame, a lens pivoted within the frame to lie therewithin in the plane of the frame, means adapted to hold the lens in extended position when it has been rotated substantially 90 degrees on its pivot, in which position the height of the frame is substantially equal to the focal length of the lens, means adapted to hold 130

the lens in extended position when it has been rotated substantially 180 degrees from its position within the frame, and resilient means adapted to urge the lens holding

5 means to hold the lens in extended position.

6. In a device of the character described, a split resilient frame having a spring tendency to close the split ends and having ex-

tending finger portions and a lens having a projecting hinge member engaged by the 10 split ends, said lens being frictionally held in the split frame when closed and between the finger portions when open and in any position in between through the resiliency of the split frame.

DENIS HENRY O'MEARA.
